UNITED STATES PATENT OFFICE.

JAMES H. EGAN, OF VENTNOR, NEW JERSEY.

REGISTER-OPERATING MECHANISM.

Original application filed November 8, 1919, Serial No. 336,648 Divided and this application filed April 22, 1920, Serial No. 375,842. Renewed September 1, 1922. Serial No. 585,837.

To all whom it may concern:

Be it known that I, JAMES H. EGAN, a citizen of the United States, residing at Ventnor, in the county of Atlantic and State 5 of New Jersey, have invented certain new and useful Improvements in Register-Operating Mechanism, of which the following is a specification.

This application is a division of my allowed application S. N. 336,648 filed November 8, 1919 for a vending machine on which Patent #1,365,469, issued January 11, 1921.

Said application includes a coin separating device, a register operating device, and 15 a coin controlled device, and the present application relates to the register operating mechanism.

The machine is of that type in which a check or token is delivered upon the deposit 20 of a particular coin, and is particularly useful at soda fountains and other places where it is customary for the purchaser to buy a check which is surrendered when the goods are delivered.

As disclosed in my said allowed application the machine includes a coin separator which will separate coins of different values and direct the same to different runways at opposite sides of the machine. The details 30 of the coin separator have been omitted from the present case which is limited to the register operating device, but it will be understood that the coin separator is used practically.

By means of the present invention a register is operated at each actuation of either side of the apparatus, the register being moved two steps when a 10¢ check is delivered, and one step when a 5¢ check is 40 delivered.

In the accompanying drawings Fig. 1 is a side elevation of the machine. Fig. 2 is a similar view with one of the side plates removed. Fig. 3 is a detail similar to Fig. 2 45 with the parts in different position. Fig. 4 is a front elevation. Fig. 5 is a perspective of a tripping device.

The separating mechanism includes a casting 50 6 with an inlet slot on neck 7, and by means of ribs one of which is indicated at 6 coins of different values are separated, as described in said patent, and for delivery of the 5¢ and 10¢ checks respectively the machine is made double, that is, it has two 55 delivery mechanisms assembled on opposite

sides of a single support. A ten cent check will be directed to one mechanism and a five cent check to the other, and the ten cent and five cent pieces respectively will be delivered in such manner as to produce a single operation of said mechanisms respectively. Inasmuch as both delivery mechanisms are the same in construction, a description of one will answer for both.

The central supporting member or plate 65 of the delivery mechanism is indicated at 15 and it consists of a casting which stands edgewise and on top of which the separating case 6 is mounted. At each side this supporting plate has formed therein a runway 70 16, the upper end of which is in line with the passage between ribs on the respective sides as described in said patent, so that the five and ten cent checks are delivered by the separating device to the respective runways. In Fig. 2 the runway shown happens 75 to be the five cent runway. This runway leads downwardly, with a bend, to a discharge outlet 17, from which the check is delivered when the device is operated. 80

Rotatably mounted in a recess in the plate or frame 15 is a star wheel 18, which turns on a pivot 19 by the weight of the checks. This star wheel has recesses 20 corresponding in size and shape to the runway 16 and 85 they act to stop a check in its passage down the runway, but when the wheel turns, the check is allowed to drop to the outlet opening 17. A finger 21 at the top of the runway, acts as a guide to deliver the checks 90 from the separating device into the runway. The runways 16 and wheels 18 are enclosed or covered by side plates 22, fastened to the sides of the middle plate 15.

The turn of each wheel is controlled by 95 an escapement, these escapements being actuated respectively by the five and ten cent coins. Each escapement consists of an irregular lever 23, pivoted at 24 to the side of the plate 15. On one side, the lever has 100 an offset finger or projection 25, which is so located as to engage in front of one of the teeth of the star wheel as shown in Fig. 3, the extending end 26 of the lever acting as a weight to assist in dropping the lever to 105 engagement. On the opposite side the lever has a projecting finger 27 which projects through a slot 28a in the side plate 22 and extends outwardly or sidewise a sufficient distance to bring it in line with the slot 110

outlet 12 at one side of the separating device or the slot outlet 12^a at the other side of the separating device. Obviously the outlet for the five cent piece will be on the side having the five cent checks. When the coin falls from said outlet, it will strike the finger 27 and tilt the lever 23 to the release position, as shown in Fig. 2, permitting the star wheel controlled thereby to turn and deliver the 10 check.

The coin then drops into the casing (not shown), in which the machine is enclosed.

The lever 23 is also provided with a cam finger or projection 28 which is located in 15 the line of movement of the points of the star wheel, and as the wheel turns one of these points will engage said cam with a wiping action and will then tilt the lever so that the finger 25 will catch the next tooth in 20 advance, as shown in Fig. 3 and thus stop further turn of the wheel until the escapement is again released by the deposit of another proper coin.

I also provide a register for indicating the 25 number of operations. This register is indicated at 30 and at each end its shaft 31 is provided with a ratchet wheel 32, adapted to be engaged by hook 33 at the end of a pawl 34, which is connected at its other 30 end by a pivot pin 35 to a lever 36, which is pivoted at 37 to the supporting plate 15, and has a finger 38 projecting into position to be engaged by one of the teeth of the star wheel. When the wheel turns, the lever 35 is rocked on its pivot and this pulls the pawl 34, whose finger 33 engages a tooth of the ratchet 32 and turns the register shaft. After the point of the star wheel passes the finger 38, as shown in Fig. 3, the lever 36 drops back and the pawl 34 rides up and drops over the next tooth of the ratchet 40 wheel for the next operation. The register counts the number of operations in numbers of nickels, but as one side is a ten cent operation, I arrange to turn the ratchet wheel two steps when that side is operated. This is done by making the pivot connecting 35 of the pawl 34 at an outer point 35^a on the lever 36. This increases the extent of the 45 movement of the pawl 34 so that on the back slip it will ride over two teeth of the ratchet 32 and so when operated will turn the register two steps. Hence, on the five cent side, the pawl 34, is connected to the lever 36 at the point 38, while on the ten cent side it is 50 connected to said lever at the point 35^a.

In operation, the attendant will first load the machine by depositing a number of five and ten cent tokens or checks in the slot 7, 60 and the separating device will pass these tokens respectively to the runways 16 at the opposite sides of the middle plate, where they will be caught and held by the respective star wheels. Assuming that the pur-

chaser desires a five cent check, he deposits 65 a five cent piece in the slot 7. This will be guided through the casing 6 in the manner above described and will be discharged at the outlet 12 and will drop thence onto the finger 27, releasing the escapement in the 70 manner above described and will be discharged at the outlet 12 and will drop thence onto the finger 27, releasing the escapement in the manner above described and permitting 75 the star wheel to turn one step and deliver one check through the opening 17. The escapement, after one check is passed, will catch and stop the star wheel, the parts being reset for the next operation. If a customer desires a ten cent check, the same 80 operation will take place except that the ten cent piece deposited will be delivered to the opposite side of the machine, from which a ten cent check will be delivered.

It will be appreciated that the separating 85 device could be used for the separation of coins or the like independently of the delivery mechanism, but the two when combined form an apparatus which will be found very useful in selling five and ten cent articles or checks of different values. It has the advantage that all the checks and coins are deposited in the same place, thus avoiding confusion and a duplication of machines 90 for different values. The principles of the 95 invention may be embodied in machines of different types and no limitation in this respect is to be understood.

I claim:

1. The combination with duplicate delivery mechanisms each having a turning part and an escapement controlling the same, of a register, and means actuated by said turning parts respectively to operate the register differently.

2. The combination with duplicate delivery mechanisms mounted side by side, of a single register having a shaft, and a pawl and ratchet mechanism at each end of the shaft, and means actuated by the delivery 100 mechanisms respectively to operate the corresponding pawl and ratchet mechanism.

3. The combination of a central supporting plate, duplicate delivery mechanisms supported at opposite sides of said plate, 115 each mechanism having an article delivering turning part, a single register supported at the edge of the plate, and said register having an operating device at each end thereof, and means actuated by the delivery mechanisms respectively to operate the respective devices.

In testimony whereof, I affix my signature.

JAMES H. EGAN.
